Primary Examiner — Karen E Kearney*Assistant Examiner* — Kathleen Jones(74) *Attorney, Agent, or Firm* — Remarck Law Group PLC(57) **CLAIM**

The ornamental design for a display screen or portion thereof with graphical user interface, as shown and described.

DESCRIPTION

FIG. 1 is a front view of the design in FIG. 2 showing the first image in a sequence for a display screen or portion thereof with graphical user interface within an electronic device; FIG. 2 is a front view of the first image in a sequence for a display screen or portion thereof with graphical user interface;

FIG. 3 is the second image in the sequence;

FIG. 4 is the third image in the sequence; and,

FIG. 5 is the fourth image in the sequence.

The broken lines showing the electronic device in FIG. 1 as well as the finger in FIG. 2 are included for the purpose of illustrating environmental structure; the broken lines showing portions of the graphical user interface in all FIGs. are included for the purpose of illustrating portions of the article; all broken lines form no part of the claimed design.
